Primary Examiner — Ian F Whitmore(74) *Attorney, Agent, or Firm* — Hemisphere Law, PLLC; Zhigang Ma(57) **CLAIM**

The ornamental design for a storage basket, as shown and described.

DESCRIPTION

FIG. 1 is a first perspective view of a storage basket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the storage basket thereof.

The broken lines shown in the drawings depict portions of the storage basket that form no part of the claimed design.

1 Claim, 9 Drawing Sheets(56)
